PHASE MODULATION RECEIVER

Murray G. Crosby, Riverhead, N. Y., assignor to
Radio Corporation of America, a corporation
of Delaware

Original application January 23, 1932, Serial No.
588,309, now Patent No. 2,081,577, dated May
25, 1937. Divided and this application Octo-
ber 1, 1936, Serial No. 103,505

6 Claims. (Cl. 250—20)

This invention relates to the signalling art and pertains especially to the transmission of intelligence from one geographically separated point to another by the use of phase modulated waves or carrier energy and is a division of Crosby United States application #588,309 filed January 23, 1932, Patent No. 2,081,577, May 25, 1937.

An object of my present invention is to provide a new and useful system for producing a phase modulated wave of substantially constant frequency and, briefly, to do so I provide an arrangement and a method wherein two voltages of substantially like frequency are combined less than 180 degrees or any multiple of 180 degrees out of phase to produce a resultant voltage. According to my invention, further, the relative phase of the resultant voltage is varied by varying the relative values of the voltages combined with the predetermined number of degrees out of phase.

As such procedure may introduce a certain amount of amplitude modulation in the resultant phase modulated wave, which of course is undesirable, it is a further object of my present invention to eliminate the amplitude modulation component. To do so the resultant phase modulated energy is limited by, for example, electron discharge devices operated at their saturation point, to substantially constant value.

More specifically, according to my present invention, I carry out the foregoing objects by applying to a pair of electron discharge devices voltages of like frequency a predetermined number of degrees out of phase such that the phase difference is not 0°, 180° or any whole multiple of 180° although phase differences varying slightly from 0°, 180° etc., are suitable. The outputs of the devices are so combined that there is a resultant voltage of like frequency. To vary the phase of this resultant voltage, or, in other words, the phase of the resultant carrier energy, I vary oppositely the internal impedances of the electron discharge devices. Preferably, I apply modulating voltages to screen grids of the devices and carrier voltages 90° out of phase to other electrodes of the devices as will be explained more fully hereinafter.

As described, a maximum shift of less than 180° is possible with the foregoing arrangement. To augment still further the phase shift produced by the modulating energy is a further object of my present invention. To do so, according to my invention, the phase shifted energy is frequency multiplied as a result of which the frequency multiplied output has a phase shift

multiplied by the order of the harmonic, or order of frequency multiplication.

Another general object of my present invention is to provide improved reception methods and means for phase modulated waves.

A further object of my invention is to provide a receiving system wherein the collected phase modulated energy is combined in predetermined phase relationship with energy of substantially constant frequency and phase and wherein the combined energies are then detected and translated. It is desirable, of course, to have the energy combined with the received energy in exact synchronism with the received carrier energy. To provide for such energy, I separate the carrier energy from the received energy and combine it in proper phase as will be explained more fully hereinafter with all of the received energy whereby the combined energy is in a form which may be detected to give the transmitted signal.

It is a further object of my invention to utilize heterodyning at my receiver for phase modulated waves, using preferably a local heterodyne oscillator of adjustable frequency, as for example, using a crystal controlled oscillator with replaceable crystals of different fundamental frequencies.

By heterodyning to the intermediate frequency it is possible to have all of the intermediate frequency amplification and the final detector circuits tuned to a fixed frequency so that only the tuning of the circuits ahead of the first detector and the frequency of the first beating oscillator requires adjustment for tuning in signals. This greatly facilitates the tuning operations and makes it possible to apply complicated filter or crystal circuits in the final stages of the receiver which could not be employed if it was necessary to make their frequency variable.

The use of the heterodyne principle also makes it possible to obtain energy from the final detector circuits which varies when the transmitter frequency or receiver oscillator varies, which energy can be utilized to control the frequency of the first beating oscillator in a manner to keep the receiver automatically tuned in to the desired signal.

Moreover, for short wave reception the frequency band of the high frequency stages is much greater than the band of frequencies occupied by the signal with its sidebands. This excessively wide frequency band allows noise to enter the receiver. By beating or heterodyning down to an intermediate frequency and there applying

additional frequency selectivity it is possible to limit the frequency band of the receiver to the band occupied by the signal. This results in minimum noise and interference.

5 Further, in connection with heterodyning it may be noted that the first heterodyne detector in a superheterodyne receiver serves the function of subtracting from all of the incoming frequencies, a frequency equal to that of the first beat-
10 ing oscillator. If an incoming signal of, say 10,000,000 cycles is modulated at the rate of 1,000 cycles with either phase or amplitude modulation, there will be produced sidebands 1,000 cycles above and 1,000 cycles below the carrier. In this case these sidebands have a spacing from the carrier of only 0.01% which is much too small to permit ordinary circuits to discriminate between carrier and sidebands in the manner required for detection of phase modulation. If the 15 signal with the 10,000,000 cycle carrier is beat with a first oscillator having a frequency of, say, 9,900,000 cycles, I obtain an intermediate frequency of 100,000 cycles, which contains the sidebands still spaced 1,000 cycles from the carrier 20 or an amount now equal to 1%. This separation is sufficiently great so that two band pass filters 25 may be utilized to separate the sidebands from one another in the manner described in the co-pending application of C. W. Hansell, Serial #611,050 filed May 13, 1932, Patent No. 1,999,902 granted April 30, 1935, and my copending application, Serial #565,005 filed September 25, 1931 and it is also sufficient to allow the carrier to be taken out through, for example, a crystal filter, 30 separately amplified and reintroduced with adjusted phase as described more fully herein-after.

It may seem that, since at the transmitter, increasing the frequency increases the phase shift, 40 at the receiver decreasing the frequency by heterodyning should decrease the shift. However, this is not so since there are two different processes involved. At the transmitter the frequency is raised by frequency multiplying and at the receiver it is lowered by heterodyning. When a 45 wave frequency multiplied it is passed into a harmonic generator and a harmonic is chosen for the multiplied output. Thus, only integral values of multiplication may be obtained corresponding to the 2nd, 3rd, 4th, etc., harmonics. When this sort of multiplying is applied to a 50 wave the phase or frequency shift of phase or frequency modulation is multiplied by the order of multiplication; that is, 2, 3, 4, etc. Thus, a 55 10,000 cycle wave frequency modulated by a 1,000 cycle shift has a 3,000 cycle shift when it is multiplied to 30,000 cycles. The same amount of multiplication is obtained in phase modulation.

As required by law, my present invention is 60 defined with particularity in the appended claims. However, it may best be explained both as to its structural organization and mode of operation by referring to the accompanying drawings wherein: Figure 1 is a wiring diagram of a phase mod-
65 lation transmitting system, according to my present invention.

Figures 2 and 3 are vector diagrams given in order to explain the operation of the system shown in Figure 1.

70 Figure 4 is a block diagram of a phase modulating system wherein the phase of a transmitted carrier may be shifted to an angle greater than 90 degrees.

75 Figure 5 illustrates one form of receiver, built in accordance with the principles of my present

invention, for receiving and translating a phase modulated wave.

Figures 6 and 7 and 7a are vector diagrams explanatory of the operation of the receiving arrangement shown in Figure 5.

Figure 8 is a modified form of phase modulation receiver according to my present invention.

Figures 9 and 10 are vector diagrams explanatory of the operation of the receiver of Figure 8.

10 Turning to Figure 1, illustrating a transmitter for transmitting phase modulated energy, carrier energy or potentials from an oscillation generator 2 are fed to an artificial transmission line 4, terminated by a resistance that is equal in 15 value to the surge impedance or resistance of the line 4. The generator 2 may be a crystal controlled oscillator, or any other form of substantially constant frequency oscillation generator. By virtue of the termination of the loaded line 4, 20 at the desired carrier frequency, only travelling waves appear in the inductive portion 8 of line 4.

The control electrodes or grids 10, 12 of electron discharge devices 14, 16 are tapped through blocking condensers 18, 20 to points 22, 24 at 25 inductance coil 8 which are less than 180° apart, for example, 90°. Accordingly, voltages of the same or like carrier frequency from source 2 are fed to tubes 14, 16, 90° apart.

30 The vectorial relationship of the voltages so fed is illustrated in Figure 2 for the particular case of 90 degrees separation where E_a illustrates the voltage applied to tube 14 and E_b indicates the alternating voltage applied to tube 16. Consequently in the output circuit 18 of 35 tubes 14, 16 there appears voltage E_r as shown in Figure 2. This is a resultant voltage which is of like frequency to the voltage applied from source 2.

Carrier source 2, of course, for the purpose of 40 obtaining voltages a desired number of degrees apart to be applied to the two electron discharge devices 14, 16 may take the form of two alternators mechanically tied together so that they can generate voltages 90, or any other desired 45 number of degrees apart in which case the output of each alternator would be fed across the grid and cathode of one of the tubes. Or, the transmission line for obtaining voltages of pre-determined phase displacement may be replaced 50 by a network of resistances, inductances and capacities to which energy of constant frequency is fed, each tube being coupled to portions of the network which have voltages generated there-across the desired number of degrees out of 55 phase.

By oppositely varying the output of each of the two electron discharge devices 14, 16 the resultant may be made to receive any phase as shown in Figure 3 from vector E_r to E'_r as indicated. This shift in phase is accomplished by 60 relatively decreasing the amplified voltage E_a appearing in the output circuit due to the amplifier action of tube 14 and relatively increasing amplified voltage E_b from tube 16 appearing 65 in the output circuit and vice versa.

In order to cause this opposite variation in voltages in tubes 14, 16, modulation energy from a suitable source 24 and amplified by push-pull amplifier 26 is fed as indicated in opposite phase 70 to the screen grids 28, 30 of tubes 14, 16. Consequently, the internal impedance of the two tubes is varied oppositely and, as a result, their outputs are varied inversely to their internal impedances, thereby causing a phase shift of the 75

resultant energy appearing in the output circuit 18 of the tubes. The phase modulated energy so appearing in the output circuit 18 of electron discharge devices 14, 16 may then be amplified by a suitable amplifier 32 and radiated or propagated through space in the form of electromagnetic wave energy by means of a suitable antenna 34.

As will be evident from an inspection of Figure 3, the greatest amount of phase shift possible with the scheme so far described is a value less than 180 degrees, or with 90 degrees phase displaced voltages, 90 degrees; and it is also evident that this arrangement introduces a small amount of amplitude modulation. To eliminate the amplitude modulation the power amplifier 32 should be operated at all times to its saturation point. To increase or augment the relative amount of phase modulation, the apparatus 20 thus 32 should include also some form of frequency multiplier.

Such an arrangement is shown diagrammatically in Figure 4 wherein rectangle 36 indicates all of the apparatus of Figure 1 with the exception of power amplifier 32 and antenna 34. The output of the phase modulator may be fed to a harmonic generator or frequency increaser 38, which, by multiplication in frequency of the output of apparatus 31 will cause an increased phase shift in the multiplied frequency energy corresponding to the order of its harmonic, or order of frequency multiplication.

To eliminate amplitude modulation introduced by either the phase modulation or the frequency multiplication, the frequency multiplier is followed by a limiter 40 whose output, in turn, is fed to power amplifier 32. If desired, the limiters may be placed ahead of the frequency multiplier, or, limiters may be used both ahead of 40 and behind the frequency multiplier.

Figure 5 illustrates a system for receiving, detecting and translating electromagnetic waves propagated by a transmitter such as described in Figures 1 and 4. Propagated energy is collected upon a suitable collecting antenna 42 and beat to a suitable band of intermediate frequencies by the action of heterodyning apparatus 44 of known construction including a variable frequency heterodyning oscillator variable so that signals over a wide range of frequencies may be received. The intermediate frequency energy so derived is amplified to a constant value by the action of intermediate frequency amplifier and limiter 46. A portion of the energy of the intermediate frequency band is fed to filter 48 which filters out energy only of the carrier frequency and is fed to a carrier amplifier and limiter 50.

The remaining portion of the intermediate frequency energy is fed to electron discharge devices 52 through the action of transformer 54. The limited carrier frequency energy, however, is fed through a phase adjusting device 56 and transformer 58 to the input side of the electron discharge device 60 whose anode is connected as shown in parallel with electron discharge device 52. The phase adjusting device 56 is so adjusted that the potentials fed to tube 60 are substantially 65 90 degrees out of phase to the potentials fed to tube 52 as indicated in Figure 6 wherein 70 E_{is} illustrates vectorially a potential fed to tube 52 and E_e indicates the potential fed to tube 60.

Now, with the reception of a non-modulated wave, the output of detector 62 will be substantially 75 constant as a result of which no sound will

be heard in the transmitting device or phones 64. However, as a phase modulated wave is received, a resultant amplitude modulated current will be present in the primary of transformer 66. Consequently, detector 62 will, through the intermediary of low frequency amplifier 70 produce sound in the transmitting device or ear phones 64. An instantaneous vectorial diagram during the reception of phase modulated signals for the arrangement shown in Figure 5 is given 10 in Figures 7 and 7a, the resultant electromotive force E' fed to the control electrode of detector 62, varying, of course, with the phase shift of the phase modulated wave E' . Of course, the same result may be obtained by feeding energy 15 from a synchronously run local oscillator to the secondary of transformer 54 or the primary of 20 58 rather than use the carrier apparatus 48, 50, 56, 58, 60. However, the arrangement shown is preferable in view of the known difficulties of 25 synchronously operating a local oscillator.

Moreover, it is to be clear that heterodyning though desirable and preferable in a phase modulation receiver, is not essential. In the event that heterodyning is not used at the receiving 25 end, amplifiers 44, 46 take the form of radio frequency amplifiers and the carrier filter 48 rather than passing the mean frequency of an intermediate band of frequencies passes the mean frequency of the received radio frequency band. 30

Another desirable form of receiving apparatus is shown in Figure 8. As indicated, intermediate frequency energy is fed to the control electrodes of detector tubes 80, 82 cophasally as shown by the vectors E_s in Figures 9 and 10, while filtered 35 carrier energy is fed to the control electrodes or grids of the detectors 80, 82, 180° out of phase, as shown by the vectors E_c of Figures 9 and 10. Amplitude variations characteristic of the phase variations and of the signal modulations will be 40 produced in the anode circuit energy.

I claim:

1. In a phase modulation signalling system the method of demodulating carrier wave energy the phase of which has been modulated in accordance 45 with signals which includes the steps of, collecting phase modulated wave energy, heterodyning said wave energy to a lower frequency to increase the percentage of frequency spread between the carrier and sideband energy of said 50 lower frequency, limiting the amplitude of said wave energy of lower frequency, producing unmodulated energy characteristic of said carrier of said lower frequency limiting the amplitude of 55 said produced unmodulated energy and combining said limited unmodulated energy with amplitude limited sideband energy of said lower frequency in substantially phase quadrature relation to produce resultant energy characteristic 60 of the phase modulations on said collected energy.

2. The method of demodulating high frequency oscillatory energy the phase of which has been modulated in accordance with signals which includes the steps of, limiting the amplitude of said phase modulated oscillatory energy, reducing the frequency of said amplitude limited oscillatory energy and simultaneously increasing the degree of phase modulation thereon to thereby produce characteristic energy of lower frequency, producing oscillatory energy characteristic of the carrier wave of said energy of reduced frequency limiting the amplitude of said produced oscillatory energy, separating said produced amplitude limited oscillatory energy into 70 75

- two portions of opposed phase, combining amplitude limited sideband energy of said reduced frequency with both of said portions in substantially phase quadrature, and differentially combining the resultants produced by said first combining steps to produce a resultant which varies in amplitude in accordance with the phase modulations on said oscillatory energy.
3. The method of demodulating oscillatory energy modulated in phase at signal frequency which includes the steps of, reducing said oscillatory energy to a lower frequency and simultaneously increasing the degree of phase modulation of said oscillatory energy of reduced frequency, limiting the amplitude of said energy of reduced frequency, separating a portion of the energy of said reduced frequency and removing therefrom all phase deviations, and impressing said energy from which the phase deviations have been removed on energy of said reduced frequency in substantially phase quadrature to produce a resultant characteristic of phase modulations on said energy.
4. In a system for demodulating phase modulated energy, a heterodyne receiver including an intermediate frequency amplifier and amplitude limiter, a filter coupled to said intermediate frequency amplifier and amplitude limiter, said filter being tuned to the frequency of the carrier passed by said intermediate frequency amplifier and amplitude limiter, a pair of electron discharge devices having input electrodes and output electrodes, an indicating circuit connected with said output electrodes a circuit including an ampli-
- 5
- 10
- 15
- 20
- 25
- 30

tude limiter connecting said input electrodes to said filter a circuit connecting said intermediate frequency amplifier to said input electrodes, and a phase adjuster in one of said last two circuits.

5. Means for demodulating wave energy modulated in phase at signal frequency comprising a pair of electron discharge devices each having an anode, a cathode and a control grid, an output circuit connecting the anodes of said tubes in push-pull relation, an input circuit connecting the control grids of said tubes in parallel, an input circuit connecting the control grids of said tubes in push-pull relation, wave amplitude limiting means for impressing said wave energy on one of said input circuits, and wave amplitude limiting and phase adjusting means for impressing oscillatory energy characteristic of the carrier frequency only of said wave energy on the other of said input circuits.

6. In a system for demodulating oscillatory energy modulated in phase, a pair of electron discharge devices each having a control grid, an anode and a cathode, an output circuit coupling said anodes together, separate input circuits connected with the control grids and cathodes of said devices, wave amplitude limiting means for impressing phase modulated wave energy on one of said input circuits, and wave amplitude limiting and phase adjusting means for impressing energy characteristic of the carrier only of said phase modulated wave energy on the other of said input circuits.

MURRAY G. CROSBY.
